UNITED STATES PATENT OFFICE.

GOTTLIEB MUEHLEISEN, OF ALMA, WISCONSIN.

DAM.

1,116,100.

Specification of Letters Patent.

Patented Nov. 3, 1914.

Application filed December 13, 1913. Serial No. 806,549.

To all whom it may concern:

Be it known that I, GOTTLIEB MUEHLEISEN, a citizen of the United States, residing at Alma, in the county of Buffalo and State of Wisconsin, have invented new and useful Improvements in Dams, of which the following is a specification.

The primary object of this invention is the provision of means for retarding and 10 catching material while at the same time permitting water to flow freely through a ditch, trench or like water course.

The invention provides an obstruction in the nature of a dam which in practice will 15 prevent ditches from getting deeper or longer and which will change the course of the stream and which further will fill ditches at the lower end when such ditches carry mud or any other trash, such matter lodging 20 against the dam and remaining there while the water will flow through the obstruction, such dam holding the filling even though the same be fine, clear quick sand.

The invention provides a dam which 25 possesses a certain amount of flexibility and which may be easily placed in position, the same comprising panels or sections arranged to extend across the bottom and along the sides of the ditch, such dam comprising 30 stakes which are driven into the ground, means for holding the stakes properly spaced and a filling such as a cable which is interwoven with the stakes.

Further objects of the invention will appear as the following description is read in 35 connection with the accompanying drawing, which forms a part of this application, and in which:—

Figure 1 is a front view of a dam embodying the invention. Fig. 2 is a top plan view 40 partly in section. Fig. 3 is an enlarged horizontal section of one of the panels. Fig. 4 is an enlarged transverse section.

Corresponding and like parts are referred 45 to in the following description and indicated in all of the views of the drawings by the same reference characters.

As indicated, the dam comprises a plurality of sections or panels A and B, the 50 middle panel A extending across the bottom and the side panels B extending across the sides of the trench, ditch or other water course. The several panels or sections are of similar formation and are flexibly connected. Cables 1 act as stays to retain the 55 dam in place. Each panel or section of the

dam comprises a plurality of stakes 2 which are driven into the bed of the ditch or water course. Angle bars 3 and 4 serve to hold the stakes properly spaced, such bars having 60 openings in one of their wings, the other wings extending along the sides of the stakes. The angle bars have an opposite arrangement, that is, the horizontal flange or wing of one of such angle bars projects upstream 65 and the flange or wing of the other angle bar projects downstream. The space between the stakes and angle bars is filled by means of a cable 5 which is interwoven or interlaced with the stakes, thereby forming 70 a net or screen which obstructs the passage of filling material while admitting of the water passing freely therethrough.

The adjacent stakes of contiguous panels or sections are connected by means of rings 75 6 to hold them in alinement. Any means the equivalent of the rings 6 may be employed so long as they serve to connect the stakes of adjacent sections and prevent separation.

When constructing a dam in accordance 80 with this invention the stakes 2 are driven into the ground a proper distance apart and extend the full width of the ditch, trench or water course. The angle bars 3 and 4 serve to space the stakes and hold them in fixed 85 relative position. After the stakes have been properly positioned the space between them and the angle bars is filled by means of the cable 5 which is interwoven or interlaced in a manner well understood and as clearly 90 illustrated in the accompanying drawing.

From the foregoing description, taken in connection with the accompanying drawing, the advantages of the construction and of the method of operation will be readily 95 apparent to those skilled in the art to which the invention appertains, and while I have described the principle of operation of the invention, together with the device which I now consider to be the best embodiment 100 thereof, I desire to have it understood that the device shown is merely illustrative, and that such changes may be made when desired as are within the scope of the claims appended hereto.

It is to be understood that the device may be used as a fence and that the filling elements 5 may consist of wire. The article may be factory made and the panels may be of any relative length and type. It is further noted that the stakes 2 are adapted to 110 slip through the interlacing of the cables,

wires or like filling elements 5, thereby admitting of such stakes being driven into the ground or bed of the ditch or the like.

What is claimed is:—

5 A dam for water courses, the same comprising a plurality of panels to extend along the bottom and sides of the water course, each panel being of similar formation and comprising a plurality of stakes and upper 10 and lower angle bars having the stakes passing through the horizontal flanges thereof, said stakes having their lower ends driven

into the bed of the water course and the contiguous stakes of adjacent panels being connected, a filling interwoven with the stakes 15 of each panel between the upper and lower bars thereof and stays for holding the several panels in position.

In testimony whereof I affix my signature in presence of two witnesses.

GOTTLIEB MUEHLEISEN.
